UNITED STATES PATENT OFFICE

112,289

DESIGN FOR A CONTAINER CAP

Carl McQuinn, Decatur, Ill., assignor to Williams Sealing Corporation, Decatur, Ill., a corporation of Illinois

Application January 16, 1937, Serial No. 67,104

Term of patent 14 years

To all whom it may concern:

Be it known that I, Carl McQuinn, a citizen of the United States, residing at Decatur, county of Macon, State of Illinois, have invented a new, original, and ornamental Design for a Container
Cap, of which the following is a specification, reference being had to the accompanying drawing, forming a part thereof.

Figure 1 is a top perspective view of a container cap showing my new design, and Figure 2 is a plan view of the cap.

I claim:

The ornamental design for a container cap,
substantially as shown.

CARL MCQUINN.
